[57] CLAIM

The ornamental design for a golf bag accessory belt, as shown and described.

DESCRIPTION

FIG. 1 is a perspective view of a golf bag accessory belt of my new design with a golf bag and accessories shown in phantom;

FIG. 2 is a front elevational view of the golf bag accessory belt opened and laid flat;

FIG. 3 is a rear elevational view thereof;

FIG. 4 is a top plan view thereof;

FIG. 5 is a bottom plan view thereof;

FIG. 6 is a right side view thereof; and,

FIG. 7 is a left side view thereof.

The broken line showing of golf bag and accessories is for illustrative purpose and forms no part of the claim.
